REVOLVER

Rienzi Rice, Worcester, Mass., assignor to Harrington & Richardson Arms Company, a corporation of Massachusetts

Application April 23, 1943, Serial No. 484,149

4 Claims.

(Cl. 42—65)

This invention relates to revolvers and in particular to actions therefor.

Objects of the invention include the provision of a revolver having a removable side plate on the frame which covers and conceals the entire action when in place and when removed reveals the action for repair, assembly and disassembly.

Further objects of the invention reside in the provision of a novel revolver action including a trigger spring element which cooperates with the hammer to permit the same to be fired when the trigger is retracted but which maintains the hammer in a position wherein it cannot be fired except under trigger retraction; the provision of a lifter for rotating the magazine cylinder in combination with a removable side plate on the frame, said side plate mounting a detent for maintaining the lifter in operative position; and the provision of a revolver action including a novel hammer and trigger construction.

Other objects and advantages of the invention will appear hereinafter.

Reference is to be had to the accompanying drawing in which

Fig. 1 is a view in side elevation of a revolver embodying the invention;

Fig. 2 is a view similar to Fig. 1 with parts broken away and with the side plate removed;

Fig. 3 is a view similar to Fig. 2 but with the parts shown in firing position;

Fig. 4 is a side view of the interior surface of the side plate.

In Fig. 1 there is shown a revolver having a barrel 10, a frame 12 and a grip 14. A magazine cylinder 16 is mounted in any desired manner in the frame to rotate on an axis as is customary. The grip 14 is hollow and is closed at the sides by means of cover plates 18 which may be attached to this grip by any suitable means desired.

The frame 12 is provided with a circular aperture 20 located between the magazine cylinder and the grip and this aperture is adapted to be closed by means of a substantially circular plate 22, this plate, however, having a cut-out portion 24 to correspond to the shape of the frame in the region of the hammer 26. The side of the frame opposite from aperture 20 is solid and continuous as represented at 28 in Fig. 2, and the revolver action is all contained in the frame between the side wall 28 and plate 22. At several spaced points about the edge of aperture 20 there are provided tapped holes as at 30, these holes being incomplete and matching with semi-circular recesses 32 in the sideplate, whereby set screws 34 may be used to securely hold the sideplate in

its aperture and abutted against a lug 36 and a solid portion 38 of the frame.

A trigger 40 is mounted to pivot on a trigger pin 42 and this trigger has a rearwardly extending finger 44 for a purpose to be described. A lifter lever 46 having a forwardly extending nose for engagement with teeth 48 on the cylinder 16 is pivoted as at 50 on the trigger, and thus it will be clear that the lifter will be elevated upon each retraction of the trigger as will be seen from a comparison of Figs. 2 and 3.

A hammer pin 52 pivotally mounts the hammer 26, the latter extending below the hammer pin and having a depending lug 54 and a forwardly extending nose 56. This nose is notched at the underside of its forwardmost extent as is clearly seen in Figs. 2 and 3. A hammer spring or main spring 58 is mounted to project a rod 60 in a direction to continuously urge the hammer towards firing position, spring 58 and rod 60 being located within the grip 14 and rod 60 engaging the hammer to one side of the hammer pin 52. A hammer lifting element 62 is mounted to pivot on a pin on the hammer and element 62 is therefore movable with the hammer. A spring 64 normally maintains element 62 in its forwardmost position, limited however by a shoulder 66 on the hammer. The element 62 may therefore be depressed in towards the hammer but it cannot extend any further in a counter-clockwise direction than the position shown in the drawing.

Plate 22 is provided with an undercut portion 68 forming a shoulder 70 providing a mount for a detent 72, and when the plate is assembled, detent 72 engages the cylinder lifter 46 at the rearward edge of the latter to press it forwardly so that the nose of the lifter will engage the cylinder teeth 48.

It will be noted that in Fig. 2 the trigger finger 44 rests on the hammer nose 56 and this position is maintained by the trigger spring 74 which abuts a fixed pin 76, the latter being straddled by a trigger spring element 78 which is stepped on its upper surface as shown at 80. Element 78 is guided in its movement by part 38 of the frame. A forwardly extending pin 79 on the trigger spring element 78 engages a cam surface 80' on the trigger, and the engagement of this pin with the cam surface being below the trigger pin 42, the trigger is consistently urged in a counter-clockwise direction.

Fig. 2 shows the revolver action at rest and it will be seen that the depending lug 54 on the hammer is stopped by a high step on the trigger spring element and this step is arranged to hold

the hammer in a position just short of firing position. If the trigger is now retracted, its finger 44 will engage the element 62 and force the hammer back towards cocking position, but if the movement of the trigger is continued its finger 44 will finally slip off the free end of element 62 and the hammer will be released to fire a shell, whereupon the parts assume the position of Fig. 3 wherein the depending hammer lug 54 will come down to the lowermost step 80 and the hammer is allowed to move forwardly far enough to fire a shell. The trigger now being released by the operator's finger, will move forwardly to Fig. 2 position and the hammer will be slightly retracted on the higher step 80 to assume the position of Fig. 2. When the trigger is pulled as just described it will clearly elevate the lifter 46 to rotate the cylinder 16, and the lifter is maintained in its highest position, see Fig. 3, until the trigger is released, whereupon the lifter will return to the Fig. 2 position ready to again rise to rotate the cylinder.

If the hammer is cocked by the operator, hammer nose 56 will retract the trigger until the trigger finger 44 slips off from the hammer nose under influence of the trigger spring 14, but at this instant the hammer is fully retracted and the notch in the hammer nose will engage the end of trigger finger 44 and maintain it in cocked retracted position. Under these circumstances a very slight additional pull on the trigger will release the hammer to fire a shell.

Having thus described my invention and the

advantages thereof, I do not wish to be limited to the details herein disclosed, otherwise than as set forth in the claims, but what I claim is:

- 5 1. A revolver comprising a frame, a cylinder, a cylinder lifter, a removable side plate for the frame, and resilient means on the side plate engaging the lifter to press the latter toward the cylinder to engage and rotate the same.
- 10 2. A revolver comprising a frame, a cylinder thereon, a lifter for rotating the cylinder, means to actuate the lifter, a removable side plate for the frame, means forming a shoulder on the side plate, and a spring-pressed detent mounted on the shoulder and extending into engagement with the lifter and maintaining the latter in operative position relative to the cylinder.
- 15 3. A revolver comprising a frame, a cylinder thereon, a lifter for rotating the cylinder, means to actuate the lifter, a removable side plate for the frame, means on the removable plate forming a support, and resilient means mounted on the support and in engagement with the lifter to yieldingly press the latter toward the cylinder.
- 20 4. A firearm comprising a frame, a cylinder, movable lifter means to advance the cylinder, said frame being provided with an opening, a removable plate for closing the opening, a trigger to move the lifter means, and means on the removable plate in a position for engaging and 25 pressing the lifter means in a direction to engage the cylinder as the trigger is operated to move the lifter means.
